UNITED STATES PATENT OFFICE.

STANISLAW A. KOLTONSKI, OF BOSTON, MASSACHUSETTS, ASSIGNOR TO ELECTRIC GAS LIGHTING COMPANY, OF BOSTON, MASSACHUSETTS, A CORPORATION OF MAINE.

TELEPHONE.

No. 846,479.

Specification of Letters Patent.

Patented March 12, 1907.

Application filed December 9, 1904. Renewed March 7, 1906. Serial No. 304,781.

To all whom it may concern:

Be it known that I, STANISLAW A. KOLTONSKI, a subject of the Czar of Russia, residing in Boston, in the county of Suffolk and State of Massachusetts, have invented a new and useful Improvement in Telephones, Particularly for Interior Use, of which the following is a specification.

My invention relates to a telephone switch device.

My invention consists in new structures or parts and in new combinations of the structures, as will be more fully shown by reference to the drawings, in which—

Figure 1 is a top plan of a telephone-box, partly broken away, and of the arm on which the telephone-receiver is hung. Figs. 2 and 3 are plans of the push-buttons and contact-springs. Figs. 4 and 5 are views, partly in cross-section, showing the push-buttons, locking and unlocking devices, and base. Fig. 6 is a side view, partly in section, showing two push-buttons, their circuit connections, and the base. Figs. 7 and 8 are details showing the form and structure of the two latches. Fig. 9 is a detail in cross-section of the top plate, insulator, and under plate constituting the ringing-circuit. Fig. 10 is a diagram illustrating the circuit and circuit connections.

The box and ordinary switch mechanism, a form of which is illustrated in Fig. 1, together with the telephone-receiver hook Y, by aid of which also a circuit may be made and broken, and its connections with the circuits, and the circuits themselves are too well understood in the art to require any further description than will be made in describing my improvements.

In the drawings, A represents the ordinary telephone switch-box.

B, Fig. 6, is the support therein for the mechanism.

C C are the push-buttons pivoted at 1 to the latches D D' and preferably loosely pivoted to meet any shrinkage or displacement of the cover of the box. The latches D D' are placed above the pillars E E, having shoulders e, grooved, as shown, Fig. 4, for the guidance of the latches. The extensions of said pillars above the shoulders are surrounded by the coiled springs e e', whose function is to press out the push-button mechanism

when released. The two latches D D' to which are loosely pivoted at 1 the push-buttons C, have a center projection d, fitting down into the helical springs e' e', mounted thereon. The latch D' carries on d' the insulating-cam d², located behind the circuit-springs c g and immediately above the circuit-springs a b, as shown, Fig. 6, whereby depression of the push-button will by means of the insulating-cam d² first crowd the springs a b into contact with the springs c g, then separate said springs, then crowd the springs c g into contact with the ringing-circuit I H; but, as shown, Fig. 2, upon removal of pressure the cam d² returns until the nose d³ (which, as shown, Fig. 8, is bent out of plane with the main body of the latch) locks on the bar F, as in Fig. 5, thus separating springs c g from I H, leaving springs c g in contact with springs a b, as shown, Fig. 3. The latch D carries on its arm d' a similar insulating-cam which operates in a similar way.

It will be understood that any number of push-buttons and latches may be used in connection with the bar about to be described. The locking-bar F serves the purpose of two bars in connection with any desired number of the latches and is mounted on the supports f f, Fig. 6, and connects by its arm f' with the arm f², rigidly pivoted to the receiver-hook arm Y. The arm f' is connected to the arm f² by an angle lever-hook f³, which is loosely pivoted at its angle on the arm f², so that when the arm Y is brought down by the receiver the hook part of f³ moves the arm f', which arm in moving disengages the latches D D', and thereupon the hook part of f³ swinging on its pivot and its other arm abutting against the stop f⁴ rises above arm f', which thereupon returns to its position by aid of a proper spring. (Not shown.) This bar F passes within the space 2 of the latch D and the space 2 of the latch D', Figs. 7 and 8.

In Fig. 10 it will be seen that the circuit-wires c' g' are attached to the springs c g and wires a' b' to the springs a b.

I will now describe the operation of my apparatus, which is shown in normal condition out of use in Fig. 6. The party desiring to call any one of the numerous stations with which he is connected presses upon a push-button corresponding with the desired station, whereupon the springs c g contact with

1 H, establishing the ringing-circuit, (see Fig. 2 and Fig. 10,) and the bell at the signaled station rings. Upon release of pressure upon the push-button the nose d^3 of latch D' 5 catches on bar F, as shown in Fig. 5, or the nose d^3 of latch D catches on bar F, as shown, Fig. 4, (according to which latch is in operation,) and the ringing-circuit is broken, as shown, Fig. 3, while the springs e g contact with springs a b, thus completing the talking-circuit, as also shown, Fig. 3 and Fig. 10. The receiver being removed from hook Y either before or after releasing the push-button, the conversation proceeds. It is evident that 15 upon finishing conversation with this station another station may be called by pushing any other button, which will release the first button. Upon hanging up the receiver the push-button is also restored to its normal 20 position by the tilting of the locking-bar in the usual way, which disengages the locking-bar f' from the nose d^3 , whereupon the coiled spring e' retracts the latch D.

Having described my invention, what I 25 claim is—

1. In an electrical switch, a latch having two lateral arms, one arm having a catching-nose bent out of plane of the main body of the latch to avoid interference with a twin latch, 30 and the other carrying a cam, a cam so carried, and means for guiding said latch.

2. In an electrical switch, a twin latch having a lateral cam-carrying arm, a cam thereon, a vertical leg or prong provided with a catching-nose, and means for guiding said latch.

3. In an electrical switch, a latch having two lateral arms, one arm having a catching-nose bent out of plane of the main body of the latch to avoid interference with a twin latch, 40 and the other carrying a cam, a cam so carried, means for guiding said latch, and a push-button mounted thereon.

4. In an electrical switch, a twin latch having a lateral cam-carrying arm, a cam thereon, a vertical leg or prong provided with a catching-nose, means for guiding said latch, and a push-button mounted thereon.

5. In an electrical switch, the combination of a latch having two lateral arms, one arm having a catching-nose, the other carrying a cam, a cam so carried, and means for guiding said latch; with a twin latch having a lateral cam-carrying arm, a cam thereon, a vertical

leg or prong provided with a catching-nose, and means for guiding said latch.

6. In an electrical switch, the combination of a latch having two lateral arms, one arm having a catching-nose bent out of plane of the main body of the latch to avoid interference with a twin latch, the other carrying a cam, a cam so carried, and means for guiding said latch; with a twin latch having a lateral cam-carrying arm, a cam thereon, a vertical leg or prong provided with a catching-nose, and means for guiding said latch.

7. In an electrical switch, the combination of a latch having two lateral arms, one arm having a catching-nose and the other carrying a cam, a cam so carried, and means for guiding said latch; with a twin latch having a lateral cam-carrying arm, a cam thereon, a vertical leg or prong provided with a catching-nose, means for guiding said latch, and a locking-bar mounted between said latches.

8. In an electrical switch, the combination of a latch having two lateral arms, one arm having a catching-nose bent out of plane of the main body of the latch to avoid interference with a twin latch, the other carrying a cam, a cam so carried, and means for guiding said latch; with a twin latch having a lateral cam-carrying arm, a cam thereon, a vertical leg or prong provided with a catching-nose, means for guiding said latch, and a locking-bar mounted between the said latches.

9. In an electrical switch, the combination of a latch having two lateral arms, one arm having a catching-nose and the other carrying a cam, a cam so carried, and means for guiding said latch; with a twin latch having a lateral cam-carrying arm, a cam thereon, a vertical leg or prong provided with a catching-nose, means for guiding said latch, and a locking-bar mounted between said latches; a receiver-hook, properly connected with said locking-bar, adapted to release the latches from the locking-bar when the receiver is hung upon the hook; all substantially as described and shown.

In witness whereof I hereunto set my hand this 5th day of December, 1904.

STANISLAW A. KOLTONSKI.

In presence of—

FRED C. CHAMBERLIN,
MICHAEL LUCEY.
